UNITED STATES PATENT OFFICE.

THOMAS JEFFERSON FLAGG, OF NEW YORK, N. Y.

DESIGN FOR SUSPENDER-ENDS.

Specification forming part of Design No. 7,243, dated March 17, 1874; application filed July 28, 1873.
[Term of Patent 14 years.]

To all whom it may concern:

Be it known that I, THOMAS JEFFERSON FLAGG, of the city, county, and State of New York, have invented a Design for Suspender-Ends, of which the following is a specification:

The nature of my design is represented in the accompanying drawing.

A represents the body of the pair of suspender-ends, which is faced with a light-colored leather, such as kid or calf skin, the said facing being, by preference, backed with a layer of strong leather to sustain the strains. At each end of the pair of suspender-ends is what I term the button-hole leaf-facing, B or C, made of a highly-colored leather, say of red, blue, green, or other highly-colored morocco. This leaf-facing surrounds the button-hole, and is stitched around the button-hole, and also at its edges, to the body of the suspender-ends.

As the body and the button-hole leaf-facing are of different colors, the latter appears distinctly projected upon the former and ornaments the suspender-ends. The outlines of the leaf-facing may be varied, the ornamental effect being produced by the projection of the button-hole leaf-facings of one high or bright color upon the ground of a different color, formed by the face of the body of the suspender-ends.

What I claim as my invention is—

The herein-described ornamental design for suspender-ends, formed by a button-hole leaf-facing differing in color from the body, as shown and set forth.

THOMAS J. FLAGG.
